United States Patent Office

Des. 215,199

Patented Sept. 16, 1969

215,199

LUGGAGE LOCK OR SIMILAR ARTICLE

Anthony N. D'Elia, New York, and Edward M. Stolarz, Yorktown Heights, N.Y., assignors to Presto Lock Co., Inc. Garfield, N.J., a corporation of New York

Filed May 29, 1968, Ser. No. 12,136

Term of patent 14 years

Int. Cl. D8—03

U.S. Cl. D8—122

FIG. 1

FIG. 2

FIG. 3

FIG. 4

FIG. 5

FIG. 6

FIG. 1 is a top plan view of a luggage lock or similar article embodying our new design;

FIG. 2 is a front elevational view;

FIG. 3 is a rear elevational view;

FIG. 4 is an end elevational view looking toward the left end of the article shown in FIG. 1;

FIG. 5 is an end elevational view looking toward the right end of the article shown in FIG. 1; and

FIG. 6 is a bottom plan view.

The essential features of our design reside in the full line showing thereof.

We claim:

The ornamental design for a luggage lock or similar article, as shown and described.
